(57) **CLAIM**

The ornamental design for a stylus holder, as shown and described.

DESCRIPTION

FIG. 1 is a front/right/top perspective view of a stylus holder, according to my claimed design, shown in a first state of use with additional environmental subject matter; FIG. 2 is a front/right/bottom perspective view of the stylus holder of FIG. 1;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front/right/bottom perspective view of the stylus holder of FIG. 1, shown in a second state of use with additional environmental subject matter.

Broken lines depicting a hand in FIG. 1 and depicting the stylus in FIG. 9, represent environmental subject matter and form no part of the claimed design. All other broken lines represent portions of the stylus holder that form no part of the claimed design.
